UNITED STATES PATENT OFFICE.

PETER H. MACKIE, OF MAXWELTON, WASHINGTON.

PILE-DRIVER HAMMER.

1,307,590.

Specification of Letters Patent. Patented June 24, 1919.

Application filed May 22, 1917. Serial No. 170,186.

To all whom it may concern:

Be it known that I, PETER H. MACKIE, a citizen of the United States, and resident of Maxwelton, Island county, Washington, have invented certain new and useful Improvements in Pile-Driver Hammers, of which the following is a specification.

My invention relates to pile driver hammers and consists of a hammer so constructed that a spring may be interposed between the hammer and the hoisting line, through which spring the effort of raising the hammer is transmitted, whereby the strain upon the line when starting the upward movement of the hammer is reduced and, in consequence, the life of the hoisting line is increased.

The object of my invention is to provide a spring connection of this sort to thereby eliminate breakage of the line and sudden strains upon the hoisting machinery.

In the accompanying drawings I have shown my invention embodied in the form of construction which is now most preferred by me.

Figure 1 is a central vertical section through a hammer constructed in accordance with my invention.

Fig. 2 is a transverse section taken on the line 2—2 of Fig. 1.

The hammer body 1 may be of any desired or suitable type of construction, except as herein otherwise specifically pointed out. The hammer is provided with a bore 2 which extends from the upper end of the hammer downwardly. This bore is of considerable size. Within it is placed a coiled spring 3, which is necessarily of heavy construction in order to support the weight of the hammer and the strain caused by quickly starting the same. Beneath the spring 3 is a piston disk 4. This piston disk forms the member through which compression is applied to the spring and may, therefore, be called a compression disk.

In the upper end of the bore 2 is placed a collar 5. This collar and the hammer, are provided with coöperating means for securing the collar in place so as to prevent its removal. This collar acts as a thrust support for the spring 3. The means adopted for securing the collar in place as herein shown, consist in providing the collar and the hammer with registering openings which are adapted to receive the locking key 6. The locking key may be secured against ac-

cidental removal as by the use of a set screw 7, or in any other suitable manner.

The connection of the hoisting line with the hammer through the spring, employs a tension member which is herein shown as consisting of the U-bolt 8, the two sides or arms of which pass through the collar, one on each side of the locking key 6, and also through the piston or disk 4. Nuts 80, 65 placed beneath the piston or disk 4, support the strain of lifting the hammer. The bent end of the U-bolt should project above the collar 5 enough to permit attachment of the hoisting line thereto.

If it is desired, a cushioning disk 9, which may be of wood, is placed at the extreme bottom of the bore and is engaged by the ends of the U-bolt 8.

In operating a pile driver, it is customary 75 for the engineer to catch the hammer and apply the lifting effort as quickly as possible after it has struck the pile on the downward movement. This lifting effort is applied with considerable force and produces a 80 heavy strain upon the hoisting line as the momentum of the engine parts is added to the normal pull of the engine to overcome the inertia of the hammer.

Also, it often happens that the friction 85 clutch of the hoisting engine is applied a little too soon and the line is tightened before the downward drop of the hammer has been entirely spent. For both of these reasons the hoisting line is regularly subjected to strains which are much above normal. For this reason the life of such a line is short.

For these reasons it has been customary 95 to employ a section of Manila cable of sufficient length to extend from the hammer to the hoisting sheaves at the upper end of the guides for the hammer. A Manila cable has, when new, a certain spring or stretch of the cable which is brought into play when excessive strains are applied. However, the cable will soon have all of this stretch taken out of it and it then does not act to compensate for these abnormal strains. Moreover, the price of Manila cable for the same work is 100 much above that of a wire cable.

By employing the spring as herein described, I can use a wire cable extending from the hammer to the hoisting engine and avoid the damage which would otherwise be 110 caused thereto by the excessive strains frequently applied to such a line. Its life

would therefore be much extended and its cost be much less than that of a Manila cable.

The use of the spring has certain other incidental advantages. When the hoisting strain is released to permit the line to drop, the expansion of the spring will act to quickly start the line running out, even before the hammer can get under way. In consequence, the hammer, while falling, has less drag upon it caused by the necessity of pulling out its hoisting line and will therefore fall more rapidly and strike harder.

Similarly, the action of the spring at the beginning of the upward or hoisting movement of the hammer, will accelerate the starting of the hammer. It is thus possible to operate at a somewhat higher rate and also to strike a harder blow.

20. What I claim as my invention:

1. A pile driver hammer having a piston receiving bore extending downward from its

upper end, a piston-like disk fitting said bore, a lifting rod connected with the disk and extending out of the bore, a spring in said bore acting to hold the disk down, a collar fitting the outer end of the bore and engaging the outer end of the spring, and means for locking the collar in place. 25

2. A pile driver hammer having a longitudinally extending spring-receiving bore opening upwardly, a coiled spring in said bore, an abutment member engaging the upper end of said spring, a piston-like disk engaging the lower end of the spring, a U-bolt 30 extending downwardly within the spring and secured to said piston disk and a holding key for the abutment member passing through said abutment member and between the sides of the U-bolt. 35

Signed at Seattle, Washington, this 16th day of May, 1917.

PETER H. MACKIE.
